2 SHEETS—SHEET 2.

UNITED STATES PATENT OFFICE.

ROBERT H. HAWKINS, OF CROCKER, MISSOURI.

ROAD-MACHINE.

1,318,555.

Specification of Letters Patent. Patented Oct. 14, 1919.

Application filed February 25, 1919. Serial No. 279,033.

To all whom it may concern:

Be it known that I, ROBERT H. HAWKINS, a citizen of the United States, residing at Crocker, in the county of Pulaski and State of Missouri, have invented certain new and useful Improvements in Road-Machines; and I do hereby declare the following to be a full, clear, and exact description of the invention, such as will enable others skilled in the art to which it appertains to make and use the same.

This invention relates to road machines, and the principal object is to provide a machine of this character for use in grading and recrowning the surfaces of roads in a novel and efficient manner.

Another object of the invention is to provide a road machine embodying a pair of rotary scrapers for scraping the dirt from the sides of the road toward the center, so that the rollers which follow immediately in rear of the scraper can roll the dirt down into the wagon and horse tracks as well as any ruts that may be present.

With these and other objects in view as will appear as the description proceeds, the invention comprises the various novel features of construction, combination and arrangement of parts as will be fully described hereinafter and afterward specifically claimed.

In the drawings,

Figure 1 represents a plan view of the road machine.

Fig. 2 represents a side elevation thereof.

Fig. 3 represents a transverse sectional view through a portion of one of the rotary scrapers, and

Fig. 4 represents a fragmentary detail perspective view of the connection of the main frame with the front running gear.

In order that the construction and operation of the invention may be readily comprehended by those skilled in the art to which the invention relates, I have illustrated an approved embodiment thereof in the accompanying drawings and will now proceed to fully describe the same, in connection with said drawings, in which 1 indicates the front or narrow portion of the main frame and 2 the rear and comparatively wide part, said latter part having connected thereto by suitable hanger straps 3, a plurality of concrete rollers 4 and 5, each of which has its opposite ends bound with a reinforcing metallic band 6 to pre-

vent the edges from crumbling or breaking while in use.

An arch frame 7 is mounted transversely of the main frame immediately in advance 60 of the rear portion and is connected to and braced to the wider portion 2 of the main frame by suitable braces 8. 9 are concrete ground-packing rollers having their opposite ends provided with metallic reinforcing bands 10, each of said rollers being fixed on a shaft 11 journaled in suitable bearings carried by the main frame and the opposite ends of the arch frame 7. A bevel gear 12 is fixed on each shaft 11 and meshes with a 70 bevel gear 13 fixed on a stub shaft 14 journaled in a bearing 15 attached to the under side of a platform 16 mounted on the part 1 of the main frame.

A rotary scraper 17 is mounted on each 75 side of the front portion of the main frame and extends forwardly and outwardly at an angle thereto, as clearly shown in Fig. 1. Said scrapers have their axes in a substantially horizontal plane, and the axis of 80 said scrapers diverge forwardly or are oblique to the longitudinal axis of the machine. Each of these rotary scrapers comprises a shaft 18 on which is fixed a non-circular bar 19 to which are bolted a plurality of 85 spring scraper arms 20 arranged in staggered offset radial relation to each other. By reference to Fig. 3, it will be noted that each scraper arm is substantially semicircular for the major portion of its length, 90 while the remaining portion thereof is provided with a rebent hooked end 21 adapted to normally engage and scrape the surface of the ground. With the spring scraper arms constructed in this manner, 95 they will, while rotating, effectively scrape the surface of the road and throw the dirt in toward the center thereof without the liability of the hooked ends 21 digging into the ground. These scraper arms are detachably connected to the sides of the non-circular bar by bolts 22, so that in the event one of them should become unfit for use, it can be readily replaced by another one.

The outer end of each shaft 18 is provided with a supporting wheel 23 while the inner end is connected to the stub shaft 14 by a universal joint 24. 25 is a stay rod connecting the outer end of each shaft 18 to the main frame.

These rotary scrapers just described are adapted to be raised and lowered through

the medium of suitable lever mechanism which, in this instance, comprises a pair of levers 26 and 27 pivotally mounted intermediate their ends, as at 28, in brackets 5 mounted on the platform 16. The outer ends of the levers are connected to the shaft 18 by rods 29 while the inner ends are connected by links 30 to bell cranks 31 pivotally supported upon the platform 16. A ratchet 10 lever 32, arranged adjacent the driver's seat 33, is connected to each bell crank 31. The ratchet levers connected to each pair of levers 26 and 27 are arranged on opposite sides of the driver's seat, so that one may be 15 grasped by the right hand and one by the left hand to raise the opposite ends of the desired rotary scraper. This raising and lowering of the rotary scraper will be permitted through the universal joint 24.

20 The front part of the main frame is connected to the bolster 34 of the front running gear by a king pin 35. 36 is a coupling member secured to the front end of the main frame and projecting through a slot 37 in 25 the bolster 34 to receive the king pin 35. 38 is a suitable brace attached to the king pin between its head and the bolster 34 and to the main frame by being extended downwardly beneath the hounds 39.

30 By the use of a machine of this character, it will be noted that the rotary scrapers will scrape the dirt from the opposite sides of the road in toward the center thereof, so that the rollers following immediately will roll 35 the scraped dirt down into the horse and wagon tracks as well as any ruts that may be present. With the arrangement of the rollers as shown, it will be noted that the rollers 9 follow in the wagon tracks or ruts, 40 the rollers 5 in the horse tracks and the rollers 4 along the opposite sides of the road. By making the rollers comparatively short and individually supporting them from the main frame, provision is made for rollers to 45 adjust themselves to the crown of the road.

From the foregoing description, taken in connection with the accompanying drawings, it is to be understood that while I have described the principle of operation of the 50 invention, together with the device which I consider to be the best embodiment thereof, I desire to have it understood that such changes in construction and arrangement of parts may be made when desired as are within 55 the scope of the appended claims.

Having thus described my invention, what I claim as new is:—

1. A road machine comprising a plurality of rollers disposed in different transverse 60 positions, a frame mounted on said rollers, rotary scrapers at opposite sides of the main frame in front of said rollers and having their axes arranged obliquely relatively to

the longitudinal axis of the frame, an operative connection between each scraper and a 65 corresponding roller at the same side of the frame including a universal joint, and individual means for supporting each scraper for adjustment from the frame.

2. In a road machine, a transverse ground packing roller, a frame mounted on said roller, a scraper carried for rotation and adjustment by said frame and arranged with its axis horizontal and oblique to the longitudinal axis of said frame, said scraper being located forwardly of said roller to operate on the ground in front of said roller, means for rotating said scraper having the universal connection with one end thereof, 75 said scraper having resilient ground-engaging arms, means for adjusting said scraper up and down, and means for supporting the other end of said scraper from the ground.

3. In a road machine of the character described, a roller mounted on each side of the 80 main frame, a rotary scraper arranged on each side of the main frame and disposed at an angle thereto, each scraper embodying a shaft, resilient spring scraper arms attached to said shaft, means for driving each 85 shaft from the adjacent roller, universal means interposed between said driving means and scraper shaft, and means for raising and lowering said scraper shaft.

4. In a road machine of the character described, the combination with a rotary scraper shaft, of a plurality of resilient spring scraper arms, each arm composed of a piece of flat spring steel substantially semi-circular for the greater part of its length and rebent to form a hook for the remainder of its length for engagement with the surface of the ground.

5. In a road machine, a set of transverse rollers to roll on and pack the ground, a frame mounted on said rollers, rotary scrapers in front of said rollers and having their axes in a substantial horizontal plane and diverging forwardly obliquely relatively to the longitudinal axis of said frame, 105 said scrapers having ground-engaging arms, to operate on the ground in front of said rollers, means for supporting said scrapers for vertical adjustment from the frame, means for driving said scrapers from said 110 rollers having universal joints with the rear ends of the scrapers, and means for supporting the forward ends of the scrapers 115 from the ground.

In testimony whereof I have signed my 120 name to this specification in the presence of two subscribing witnesses.

ROBERT H. HAWKINS.

Witnesses:

GOLDIE HAWKINS,
Mrs. A. J. D. CANTRELL.
